PROCESS OF MAKING IRRADIATION CHAMBERS

Sidney O. Levinson and Franz Oppenheimer, Chicago, Ill., assignors to Michael Reese Research Foundation, a nonprofit corporation of Illinois

Original application July 8, 1944, Serial No. 544,098. Divided and this application July 20, 1948, Serial No. 39,678

3 Claims. (Cl. 49—82)

1

This invention relates to a method of making irradiating chambers and more particularly to the manufacture of a chamber in which a film of a liquid or suspension of a desired thinness may be submitted to ultraviolet, or other, irradiation. This application is a division of our copending application Serial No. 544,098, filed July 8, 1944, now abandoned.

The treatment of various substances by irradiation is widely employed for developing certain properties in the materials treated or for causing desired chemical changes in them. In the practice of such processes commercially, it is necessary to develop a standard technique for each given process. A lamp and irradiating chamber of a certain type is generally employed, the material is submitted to treatment for a definite period of time and a predetermined film thickness is employed, the variables being correlated to each other to produce the best over-all results for the particular process.

In such processes the thickness of the film of liquid or suspension is generally an important consideration. Many of the materials treated are opaque to the rays employed, in varying degrees, particularly the shorter rays generally employed in such treatments. One of the greatest difficulties heretofore encountered in such processes is the maintenance of a film of the desired thinness.

In the present invention we have provided an irradiating chamber by means of which the thickness of the treated film can be maintained uniform throughout the chamber. The chamber is formed of two flat plates. For short wave ultraviolet irradiation, the front of the chamber, that is, the side exposed to the irradiation, is made very thin and of the highest grade optical quartz. The plates are ground so that their surfaces are parallel. After the plates have been properly prepared, they are placed over a strip of metal, or other suitable material, of a predetermined thickness which serves as a spacer and the side edges of the plates are then sealed to each other by fusion. The spacer is removed, after the plates have been sealed to each other, and the unsealed ends sealed to tubes to form a chamber of the desired depth for exposing the film. By employing spacers of varying desired thicknesses, the depth of the chamber and the thickness of the film can be accurately controlled. By feeding the liquid or suspension through the apparatus under pressure or vacuum, the chamber can be kept filled at all times and the rate of flow of the material can be controlled.

In the accompanying drawings we have shown

2

one form of irradiating chamber made by our process. In this showing:

Fig. 1 is a front elevation of the irradiating chamber;

Fig. 2 is a plan view;

Fig. 3 is a view of the top and bottom walls of the chamber and the spacer strip on an enlarged scale; and

Fig. 4 is a vertical, sectional view of the irradiating chamber before removal of the spacer strips on line 4—4 of Fig. 1.

Referring to the drawings the reference numeral 1 designates a flat plate of purest optical quartz. This plate, which forms the front of the irradiating chamber, that is the side exposed to the rays, is very thin, preferably of a thickness less than 0.5 mm. A similar plate 2 forms the other wall of the irradiating chamber. The back plate may be of greater thickness and any type of quartz can be used as the rays do not pass through it. The back plate 2 does not require polishing but the plates 1 and 2 are ground so that their adjacent surfaces are parallel.

In assembling the plates 1 and 2 into an irradiating chamber which will expose a film of desired thinness, the spacer plate 3 is first placed between the plates 1 and 2 and the plates 1 and 2 are then sealed on each side by fusion or the like. The spacer plate is preferably formed of thin gauge metal but it may be formed of any material capable of withstanding the temperatures employed in fusing the edges of the plates 1 and 2 and also capable of being worked to exact dimensions to produce the desired spacing between the plates 1 and 2. After the chamber has been formed, the spacer plate is removed. This produces a cell of the desired depth and with accurate spacing between the inner faces of the plates 1 and 2 throughout the length of the cell to thereby expose a film of the desired thickness. In this manner we have made irradiating chambers, using high grade quartz for the front plate 1, with a spacing between the plates as small as 0.1 mm., but of course any desired spacing of the plates 1 and 2 and resulting depth of the treated film may be obtained.

An inlet tube 4 is sealed to one open end of the chamber and an outlet tube 5 is sealed to the other open end of the chamber. A brace or strengthening rod 6 may be connected to these tubes intermediate their ends to give greater strength to the completed chamber. By passing the liquid or suspension to be treated into the irradiating chamber upwardly through the inlet tube 4 and removing it from the chamber down-

wardly through the outlet tube 5, the flow of material through the chamber can be regulated in any suitable manner so as to keep the chamber always filled and thus expose a film of the desired thickness to the treatment. Regulation of the flow also controls the time that the material is in the irradiating chamber and exposed to the irradiation.

It will be apparent that the method and construction herein described produces an irradiating chamber in which accurate and uniform spacing of the top and bottom plates is obtained so that a film of uniform thickness and of a desired thickness may be passed through the chamber. By regulating the rate of flow, the time of irradiation may be controlled and the device may be readily assembled at a given distance from a lamp whereby uniform conditions may be obtained in treating any material. The method of forming the chamber provides a simple means whereby a chamber of a desired depth may be obtained.

In treating materials wherein contamination from outside sources must be avoided, as in biological work, the chamber possesses the additional advantage of providing a closed system. Thus the material to be treated may be delivered from a feeding flask (not shown) by suitable connection to the inlet end 4 of the chamber and may be discharged from the outlet end 5 to a collecting flask (not shown) by means of a tubing so that no contact with the air is possible from the time the material is placed in the feeding flask until the process is completed. Thus the material

is not subjected, at any time, to the hazard of chance contamination.

We claim:

- 5 1. The herein described method which comprises placing a pair of transparent plates on opposite sides of a spacer plate of the desired thickness, sealing the side edges of the plates to each other, removing the spacer plate and sealing an inlet tube to one end and an outlet tube to the other end of the plates.
- 10 2. The herein described method which comprises grinding the faces of a pair of quartz plates, one of said plates being formed of thin high grade quartz, placing the quartz plates on opposite sides of a spacer plate of a predetermined thickness, uniting the side edges of the quartz plates to each other, removing the spacer plate, and uniting each end of the quartz plates to a tube.
- 15 3. The herein described method of forming an irradiation chamber of a desired dimension throughout which comprises grinding the faces of a pair of quartz plates, one of which is formed of thin high grade quartz, placing the plates of quartz on opposite sides of a metal plate of a thickness corresponding to the desired dimension of the irradiating chamber, sealing the side edges of the quartz plates to each other, removing the spacer plate, and sealing each end of the quartz plates to a tube.
